UNITED STATES PATENT OFFICE

134,818

DESIGN FOR A BATTERY CHARGER

Albert C. Fletcher, Oklahoma City, Okla., assignor
to Quick Charge, Inc., Oklahoma City, Okla., a
corporation of Oklahoma

Application October 31, 1941, Serial No. 103,969

Term of patent 3½ years

To all whom it may concern:

Be it known that I, Albert C. Fletcher, a citizen of the United States, residing at Oklahoma City, in the county of Oklahoma and State of Oklahoma, have invented a new, original, and ornamental Design for a Battery Charger, of which the following is a specification, reference being had to the accompanying drawing, forming part thereof.

Fig. 1 is a perspective view of a battery charger, showing my new design.

Fig. 2 is a side elevational view of the battery charger.

Fig. 3 is a plan view of the battery charger.

I claim:

The ornamental design for a battery charger, as shown.

ALBERT C. FLETCHER.
